RAILWAY SIGNALING SYSTEM

Thomas W. Tizzard, Jr., Downers Grove, Ill., assignor to The Union Switch and Signal Company, Swissvale, Pa., a corporation of Pennsylvania.

Application August 7, 1941, Serial No. 405,821

16 Claims. (Cl. 246—26)

My invention relates to a railway signaling system and particularly to an improved system which employs apparatus of the type shown in application Serial No. 393,363 of George W. Baughman.

It is an object of my invention to provide an improved signaling system of the type described and arranged to facilitate control of the signaling system by remote control apparatus.

A further object of the invention is to provide an improved system of the type described and incorporating means for approach locking the switches at the entrance ends of the passing sidings without necessitating the use of additional line wires.

A further object of the invention is to provide an improved signaling system which is arranged so that when the remote control apparatus has been manipulated to condition the signals for one direction of traffic in a track stretch between passing sidings to display proceed indications, the signals for the other direction of traffic cannot be conditioned to provide proceed indications.

Other objects of the invention and features of novelty will be apparent from the following description taken in connection with the accompanying drawings.

I shall describe two forms of signaling system embodying my invention, and shall then point out the novel features thereof in claims.

In the drawings,

Figs. 1a, 1b and 1c, when placed together in the order named form a diagram showing a stretch of railway track equipped with one form of signaling system provided by my invention, and

Figs. 2a and 2b, when placed together in the order named, form a diagram showing a stretch of railway track equipped with a modified form of signaling system provided by my invention.

Similar reference characters refer to similar parts in both views.

Referring to the drawings, there is shown therein a stretch of railway track over which traffic moves in both directions. In addition, there are passing sidings M and N which are connected with the main track by means of switches MW and NW in the customary manner.

For purposes of illustration it will be assumed that the right-hand end of the track stretch is east and that the left-hand end thereof is west. Accordingly, train movements from left to right are eastbound, while train movements from right to left are westbound.

The rails of the main track are divided by in-

sulated joints into successive track sections designated 1T, 2T, 3T, etc. Each of these track sections is provided with a track circuit comprising a track battery connected across the track rails at one end of the track section and a track relay, designated TR with an appropriate prefix, connected across the track rails at the other end of the track section.

Eastbound traffic on the main track is governed by signals 2S, 4S and 6S, while westbound traffic is governed by signals 1S, 3S and 5S. The system provided by this invention is directed particularly to means for controlling the signals 2S and 4S, and the signals 3S and 5S. The signals

15 1S and 6S at the entrance ends of the passing sidings may be controlled in any appropriate manner well known in the art in accordance with traffic conditions in advance and the position of the associated switch. It is also contemplated 20 that the signals 1S and 6S will be controlled by remote control apparatus so that these signals will normally display stop indications, but may be controlled by an operator by means not shown to be governed by traffic conditions in advance.

25 In addition to the signals for the main track a signal 2SA is provided to control movement of eastbound trains from the siding M onto the main track, while a signal 5SA is provided to control movement of westbound trains from the 30 siding N onto the main track. These signals may be controlled in any appropriate manner well known in the art.

35 In the system shown in the drawings the signals are shown as being of the color light type, but it should be understood that the invention is not limited to the use of signals of this type and that any desired form of signal may be employed instead.

The signal system provided by this invention 40 is arranged to be controlled by remote control apparatus such as a centralized traffic control system. The remote control system includes a relay 5LHS associated with signal 5S, and a relay 2RHS associated with signal 2S.

45 The relays 5LHS and 2RHS are normally released and when released condition the associated signal to display its stop indication as hereinafter explained in detail. The relays 5LHS and 2RHS when picked up permit the associated signals to be controlled in accordance with traffic conditions in advance.

The relays 5LHS and 2RHS may be controlled 50 from a remote point in any desired manner, as by direct wire or by a centralized traffic control system. The details of the means for controlling

these relays are not a part of this invention and have been omitted to simplify the disclosure.

The signals 2S and 2SA, and 5S and 5SA have associated therewith lock relays 2RMR and 5LMR which are governed in accordance with the aspects displayed by the signals and by traffic conditions in the track stretch leading to the signals. Each of these relays is controlled in such manner as to be picked up when and only when both of the signals with which it is associated display stop indications, and to be released when either signal displays a proceed indication. Each of these relays is also controlled by time delay means so that when the relay is released and a train is in the vicinity of the switch, it cannot be picked up until the expiration of a time delay period unless the time delay period is eliminated by passage of a train.

In addition, each of the lock relays is controlled by traffic conditions in the detector section which includes the switch governed by the lock relay. When this section is occupied, the detector locking is effective to prevent movement of the switch, while a circuit is established to pick up the lock relay without waiting for the expiration of the time delay period.

The means for controlling the relays 2RMR and 5LMR is not a part of this invention and these relays may be controlled in any manner well known in the art. These relays, for example, may be controlled in the manner that relays RMR and LMR of Patent No. 2,093,170 to Ronald A. McCann are controlled.

Similarly, the signal 1S has associated therewith a relay 1SP which is picked up only when the upper portion of the signal displays its green or clear indication. Likewise the signal 6S has associated therewith a relay 6SP which is picked up only when the upper portion of the signal displays its green or clear indication.

The system provided by this invention has a line circuit I formed by line wires 20 and 21 and extending between signals 2S and 3S, and a line circuit II formed by line wires 22 and 23 and extending between signals 4S and 5S.

At each end of each line circuit are located line relays designated P and K together with a prefix corresponding to that of the signal with which the relays are associated.

Each of the relays P is of the stick polar type having contacts which are moved to one position when the relay winding is supplied with energy of one polarity and to another position when the relay winding is supplied with energy of the other polarity. These relays are also arranged so that their contacts when moved to either position remain in that position on deenergization of the relay winding.

Each of the relays K is of the biased polar type having contacts which are released when the relay winding is deenergized and become picked up only when energy flows in one direction through the relay winding.

The relays P control connection from the line circuits to the relays K in such manner that if the relays P respond properly to a change in the polarity of the energy supplied over the line circuits, the direction of flow of energy through the windings of the relays K will be such as to be effective to pick up the contacts of the relays K.

The arrangement of the relays P and K is not a part of this invention but is shown and claimed in application Serial No. 311,955 of Harry E. Ashworth.

Each of the signal locations is provided with a

source of direct current, such as a storage battery, not shown, the terminals of which are designated B and C.

The system provided by this invention employs continuously operating code transmitters 75CT, 120CT, and 180CT, having contacts which are opened and closed at rates such as to provide 75, 120, and 180 energy impulses a minute which are separated by periods of equal duration during which no energy is supplied.

In the drawings the relay contacts are in most instances shown directly under the winding of the relay. However, in some instances, in order to simplify the drawings, the relay contacts are shown removed from the relay winding, and where this is done the relay with which the contacts are associated is designated by appropriate reference characters placed above the contacts.

The equipment is shown in the condition it assumes when the track stretch is vacant, the switches MW and NW are in their normal positions, the upper and lower portions of signals 1S and 6S are conditioned to provide stop indications, and the remote control relays 2RHS and 5LHS are deenergized.

As relay 2RHS is not energized, its contact 25 is released and interrupts the circuit of relay 2HP so that its contact 26 is released and establishes the circuit of the red or stop lamp R of signal 2S.

As signals 2S and 2SA are both displaying stop indications, the relay 2RMR is energized and its contacts 36 and 40 are picked up to permit energy to be supplied to the west end of line circuit I, while its contact 39 interrupts the circuit for supplying energy from the decoding transformer 2DT to the relay 2J.

As signal 1S is assumed to be conditioned by the remote control apparatus, not shown, to display its red or stop indication, relay 1SP is released and its contacts 30 and 31 establish connections from a source of current to the wires of line circuit I so that energy of reverse polarity is supplied to this circuit. During the picked-up periods of the contacts of code transmitter 120CT terminal B is connected through resistance 32, front contact 33 of track relay 1TR, back contact 31 of relay 1SP, front contact 35 of code transmitter 120CT, front contact 36 of relay 2RMR, and front contact 37 of track relay 2TR to line wire 21, while terminal C is connected through back contact 30 of relay 1SP, front contact 38 of code transmitter 120CT, front contact 40 of relay 2RMR, and front contact 41 of track relay 2TR to line wire 20. During the released periods of the contacts of code transmitter 120CT the supply of energy to the west end of line circuit I is interrupted, while the line wires are connected over front contacts of relays 2TR and 2RMR, and the back contacts of the code transmitter to the line relays 2P and 2K.

The energy supplied to the west end of line circuit I is supplied to line relays 3P and 3K during the released periods of the contacts of coding relay WCR. During these periods line wire 20 is connected through front contact 42 of track relay 3TR, front contact 43 of track relay 4TR, and back contact 44 of coding relay WCR to one terminal of the windings of relays 3P and 3K, while line wire 21 is connected through front contact 46 of track relay 3TR, front contact 47 of track relay 4TR, and back contact 48 of coding relay WCR to the other terminal 75 of the windings of relays 3P and 3K.

The energy supplied to the east end of line circuit I is supplied to line relays 2P and 2K during the released periods of the contacts of coding relay WCR. During these periods line wire 21 is connected through front contact 42 of track relay 3TR, front contact 43 of track relay 4TR, and back contact 44 of coding relay WCR to one terminal of the windings of relays 2P and 2K, while line wire 20 is connected through front contact 46 of track relay 3TR, front contact 47 of track relay 4TR, and back contact 48 of coding relay WCR to the other terminal 75 of the windings of relays 2P and 2K.

The contacts of coding relay WCR are operated at 75 or 180 code frequency according as relay 4H is released or picked up. At this time relay 4H is picked up and its contact 50 establishes a circuit controlled by a contact of code transmitter 120CT for energizing relay WCR so the contacts of this relay pick up and release 180 times a minute.

The rate of operation of the contacts of relay WCR, whether they are operating at 180 or 75 code frequency, is substantially different from the rate of operation of the contacts of code transmitter 120CT. Accordingly the contacts of relay WCR and of code transmitter 120CT do not operate in synchronism, and there are frequently recurring periods during which the contacts of code transmitter 120CT are picked up and the contacts of relay WCR are released. At these times energy is supplied over the line circuit I to relays 3P and 3K. As this energy is of reverse polarity the contacts of relay 3P occupy their right-hand or reverse positions as shown, while the contacts of relay 3K respond to the impulses of energy supplied to the relay winding so that energy is supplied through the decoding transformer 3DT to relay 3H as explained in United States Patent No. 2,237,788 to F. H. Nicholson and L. R. Allison. Accordingly, the contacts of relay 3H are picked up and its contact 51 cooperates with reverse polar contact 52 of relay 3P to establish the circuit of the yellow or caution lamp Y of signal 3S.

During the picked-up periods of the contacts of coding relay WCR connection from the line circuit to relays 3P and 3K is interrupted, while energy is supplied to the east end of the line circuit. At this time relay 4H is picked up, as explained below, so the energy supplied to the line circuit is of normal polarity. During the picked-up periods of the contacts of relay WCR terminal B is connected through resistance 53, back contact 54 of relay 3SR, front contact 55 of relay 4H, front contact 43 of coding relay WCR, front contact 43 of track relay 4TR, and front contact 42 of track relay 3TR to line wire 20, while terminal C is connected through front contact 57 of relay 4H, front contact 48 of relay WCR, front contact 47 of relay 4TR, and front contact 46 of track relay 3TR to line wire 21.

As a result during those intervals in which the contacts of coding relay WCR are picked up and the contacts of code transmitter 120CT are released energy is supplied over line circuit I to line relays 2P and 2K. As this energy is of normal polarity the contacts of relay 2P occupy their normal position as shown, while relay 2K responds to the impulses of energy supplied thereto and energy is supplied through the decoding transformer 2DT to relay 2H so that contact 58 of this relay is picked up. However, at this time contact 25 of relay 2RHS is released so the circuit of relay 2HP is interrupted; and this relay is released and its contact 26 establishes the circuit of the red lamp R of signal 2S.

The relay 2H cooperates with other means, not shown, to control locking of the switch MW. This means is arranged so that the switch is locked when the relay 2H is deenergized and may be moved when the relay 2H is picked up. As the relay 2H is picked up at this time the switch MW may be moved if desired.

The equipment associated with line circuit II operates in similar manner at this time. As

signal 6S is assumed to be conditioned to display a stop indication relay 6SP is released and the energy supplied to the line circuit II during the picked-up periods of the contacts of the code transmitter 120CT is of reverse polarity.

Similarly, as relay 3H is picked up its contacts 66 and 67 establish connections such that energy of normal polarity is supplied to the line circuit II during the picked-up periods of contacts 63 and 64 of coding relay ECR. As relay 3H is picked up its contact 69 establishes a circuit to supply energy of 180 code frequency to relay ECR so the contacts of relay ECR operate at the 180 code rate. During the released periods of the contacts of the coding relay ECR the line circuit II is connected to line relays 4P and 4K. As the energy supplied at the east end of the line circuit is of reverse polarity the contacts of relay 4P occupy their reverse positions and a circuit including front contact 66 of relay 4H, and reverse polar contact 67 of relay 4P is established to light the yellow or caution lamp Y of signal 4S.

During the released periods of the contacts 10 and 11 of the code transmitter 120CT at signal 25 6S the wires of line circuit II are connected to line relays 5P and 5K so that energy of normal polarity supplied to the west end of line circuit II may feed to these relays and relay 5K responds to the impulses of energy supplied thereto so that 30 energy is supplied through the decoding transformer 5DT to the relay 5H. Accordingly, the contacts of relay 5H are picked up and contact 72 cooperates with normal polar contact 73 of relay 5P to establish the circuit of relay 5HP. However, this circuit is not complete at this time as the remotely controlled relay 5LHS is released and its contact 78 interrupts the circuit of relay 5HP. Accordingly, contact 79 of relay 5HP is released and establishes the circuit of the red or 40 stop lamp R' of signal 5S.

At this time as signals 5S and 5SA are displaying stop indications relay 5LMR is picked up and its contacts 81 and 82 establish the circuits to permit energy to be supplied to the east end 45 of the line circuit II, while its contact 84 interrupts the circuit for supplying energy from the decoding transformer 5DT to relay 5S so relay 5J is deenergized.

50 *Operation of equipment on passage of an eastbound train through the track stretch*

When it is desired to condition the track stretch for passage of an eastbound train the operator manipulates the remote control apparatus to energize relay 8RHS and its contact 25 picks up and completes the circuit of relay 2HP while contact 26 of relay 2HP picks up and interrupts the circuit of the red or stop lamp R of signal 2S and establishes the circuit of the yellow or caution lamp Y of this signal. As a result of this change in the aspect of signal 2S relay 2RMR becomes released and its contacts 36 and 40 prevent the further supply of energy to the west end of the line circuit I and connect the line circuit 60 directly to the line relays 2P and 2K so that these relays are energized whenever the contacts of coding relay WCR are picked up. In addition, on release of relay 2RMR its contact 39 establishes the circuit to supply energy from the decoding transformer 2DT to relay 2J.

At this time, as pointed out above, coding relay WCR is operating at the 180 code rate so energy of this code frequency is supplied to the line circuit, while as the line circuit is directly connected to the line relays energy of this fre-

quency is supplied to the line relay 2K. The relay 2K, therefore, follows 180 code and energy is supplied through the decoding transformer 2DT to maintain relay 2H picked up, while energy is supplied from the decoding transformer through the resonant rectifier unit RU to relay 2J. The unit RU is arranged to permit sufficient energy to be supplied through the unit to pick up the relay 2J only when the relay 2K is responding to energy of 180 code frequency. As energy of this frequency is supplied to the relay 2K at this time the relay 2J is picked up and its contact 85 interrupts the circuit of the yellow lamp and establishes the circuit of the green or clear lamp G of signal 2S.

As a result of the cutting off of the supply of energy to the west end of line circuit I, which occurs on release of relay 2RMR, relay 3K ceases to follow code and relay 3H releases and its contact 51 establishes the circuit of the red or stop lamp R of signal 3S.

In addition, on release of relay 3H its contact 69 changes the energy supplied to coding relay ECR from 180 to 75 code frequency, while its contacts 60 and 61 change the energy supplied to the west end of line circuit II from normal to reverse polarity. On this change in the polarity of the energy supplied to line circuit II and to line relay 5P the contacts of relay 5P shift to their right-hand or reverse positions and contact 73 interrupts the circuit of relay 5HP to maintain this relay released and thereby prevent the display of a proceed indication by signal 5S if the operator should manipulate the remote control apparatus so as to energize relay 5LHS.

In addition, in order to condition the track stretch to permit passage of an eastbound train the operator manipulates the remote control apparatus, not shown, to cause signal 6S to be governed by traffic conditions in advance. As the stretch is assumed to be vacant and as the switch NW is assumed to be in its normal position the upper portion of signal 6S will now display its green or clear indication, while relay 6SP will be energized and its contacts 87 and 88 will pick up and will change the energy supplied to the east end of line circuit II from reverse to normal polarity. On this change in the polarity of the energy supplied over the line circuit II to line relay 4P the contacts of this relay shift to their normal or left-hand positions and contact 67 interrupts the circuit of the yellow lamp Y and establishes the circuit of the green or clear lamp G of signal 4S.

It will be seen, therefore, that as a result of manipulation of the remote control apparatus to condition the track stretch for eastbound traffic signal 2S is conditioned to display a green or clear indication, while the supply of energy to the west end of line circuit I is cut off to thereby put signal 3S at stop and to change the polarity of the energy supplied to the west end of line circuit II so that signal 5S will be held at stop. In addition, on clearing of signal 6S the polarity of the energy supplied to the east end of line circuit II is changed so that signal 4S displays its green or clear indication. All of the eastbound main track signals, therefore, show green or clear indications, while all of the westbound main track signals show stop.

When an eastbound train enters section 1T track relay 1TR releases and its contact 33 prevents the supply of energy to the west end of line circuit I, while its contact 34 interrupts the circuit of relay 2HP so that contact 26 of relay

2HP releases and establishes the circuit of the red or stop lamp R of signal 2S.

In addition, when the train enters section 1T and track relay 1TR releases the detector locking for switch MW becomes effective to prevent picking up of the relay 2RMR and thereby prevent movement of the switch MW.

On release of track relay 1TR the remote control relay 2RHS may be released or not depending on the method of operation of the remote control apparatus. For purposes of illustration it will be assumed that this remote control system is arranged and operated in such manner that the relay 2RHS remains picked up 15 when track relay 1TR releases, and that the relay 2RHS when picked up remains picked up until it is released by reason of manipulation of the remote control system.

When the train enters section 2T track relay 2TR releases and interrupts line circuit I to thereby prevent the supply of energy over this line circuit to the line relays 2P and 2K. Accordingly, relay 2K ceases to follow code and energy is no longer supplied through the transformer 2DT to the relays 2H and 2J and these relays release. On release of relay 2H its contact 58 interrupts the circuit of relay 2HP.

In addition, on release of track relay 2TR its contact 41 establishes a circuit short circuiting the portion of the line circuit I west of the track relay, while its contact 37 establishes a circuit short circuiting the portion of the line circuit east of the track relay. As both portions of the line circuit are short circuited there is no possibility that the line relays will be improperly energized if energy is improperly supplied to either portion of the line circuit.

When the train advances into section 3T track relay 3TR releases and its contacts 42 and 46 release and additionally interrupt and short circuit line circuit I, while contacts 90 and 91 of relay 3TR interrupt the supply of energy to the west end of line circuit II, and connect this line circuit directly to the line relays 4P and 4K and thereby render operation of these relays more positive and thus maintain the display of a green or clear signal 4S.

As a result of the cutting off of the supply of energy to the west end of line circuit II relay 5K ceases to follow code and energy is no longer supplied through the transformer 5DT to relay 5H and this relay releases so that its contact 92 interrupts the circuit of relay 5HP to insure that this relay will remain released and maintain the circuit of the red or stop lamp R of signal 5S.

In addition, release of relay 5H may render the locking for switch NW effective so that this switch cannot be moved without waiting for release of the time locking means. The relay 5H may also control indication means, not shown, so that on release of the relay the indication means will operate to provide an indication of the approach of the train.

When the train advances into section 4T track relay 4TR releases and its contacts 93 and 94 interrupt and short circuit line circuit II while its contact 95 establishes the pick-up circuit of relay 4SR. This circuit also includes front contact 96 of relay 4H while when the contacts of relay 4SR pick up its contact 97 establishes a stick circuit to maintain the relay energized as long as either relay 4TR or 4H is released.

In addition, on release of the contacts of track relay 4TR its contacts 43 and 47 cut off the supply of energy to the east end of line circuit I and

connect the line circuit directly to the line relays 3P and 3K.

When the line circuit II is interrupted by release of track relay 4TR relay 4K ceases to follow code and energy is no longer supplied through the transformer 4DT to relay 4H and relay 4H releases. The relay 4H, as well as the counterpart relays at the other signal locations, is of a type which is slow in releasing so that it will bridge the intervals between the supply of impulses of energy thereto. Accordingly, on release of the contacts of the track relay 4TR the contacts of relay 4H remain picked up for a period and maintain the pick-up circuit of relay 4SR long enough for the contacts of this relay to pick up.

When the contacts of relay 4H release its contact 96 completes a stick circuit for relay 4SR, while its contact 66 interrupts the circuit of the green lamp and establishes the circuit of the red or stop lamp of signal 4S.

When relay 4SR picks up its contact 107 cuts off the supply of energy to the west end of line circuit II.

When the train advances into section 5T track relay 5TR releases and its contacts 100 and 101 additionally interrupt and short circuit line circuit II.

When the rear of the train vacates section 4T track relay 4TR picks up so that energy may be supplied to the west end of line circuit I on picking up of relay 2RMR. In addition, on picking up of track relay 4TR a pick-up circuit is established for relay 2RMR as explained in Patent No. 2,093,170 to Ronald A. McCann mentioned above. Accordingly, the relay 2RMR picks up and establishes a stick circuit to maintain itself picked up as long as signal 2S displays a stop indication, while contacts 40 and 36 of relay 2RMR establish connection from the contacts of the code transmitter 128CT to the line circuit I so that energy is supplied to the west end of line circuit I after picking up of the contacts of track relay 2TR. This energy is of reverse polarity as signal 2S is displaying its red or stop indication and relay 1SP is released.

When the rear of the train vacates section 2T track relay 2TR picks up, while when the train vacates section 3T track relay 3TR picks up and energy supplied to the west end of line circuit I feeds to line relays 3P and 3K over the circuit which includes back contacts 43 and 47 of track relay 4TR. On the supply of energy of reverse polarity to relay 3P its contacts remain in their reverse position, while on the supply of coded energy to the relay 3K energy is supplied through transformer 3DT to relay 3H. Accordingly, the contacts of relay 3H pick up and contact 51 cooperates with reverse polar contact 52 of relay 3P to establish the circuit of the yellow or caution lamp of signal 3S.

On picking up of the contacts 60 and 61 of relay 3H and of contacts 90 and 91 of relay 3TR connections are established to permit energy of normal polarity to be supplied to line circuit II after the contacts of track relay 4TR pick up. As contact 69 of relay 3H is picked up the coding relay ECR operates at the 180 code frequency.

When the train advances far enough to vacate section 4T, track relay 4TR picks up and its contacts 43 and 47 connect the line wires 20 and 21 of line circuit I to the contacts 44 and 48 of coding relay WCR so that during the released periods of these contacts energy may be supplied over the line circuit to the line relays 3P and 3K,

while during the picked-up periods of these contacts energy may be supplied to the east end of line circuit I.

At this time relay 4H is released while relay 5 4SR is maintained picked up by energy supplied over the stick circuit which includes back contact 96 of relay 4H. Accordingly, during the picked-up periods of the contacts of the coding relay WCR terminal B of the source is connected 10 through back contact 54 of relay 3SR, front contact 103 of relay 4SR, and back contact 55 of relay 4H to line wire 20, while terminal C is connected through front contact 104 of relay 4SR, and back contact 57 of relay 4H to line wire 21. 15 Energy of normal polarity is therefore supplied to the east end of line circuit I and this energy is supplied to line relays 2P and 2K during the released periods of the contacts of code transmitter 128CT. Contact 58 of relay 2H thereupon 20 picks up, and assuming that contact 25 of relay 2RHS remains picked up as explained above, completes the circuit of relay 2HP. Accordingly, contact 26 of relay 2HP picks up and interrupts the circuit of the red or stop lamp R of signal 2S and establishes the circuit of the yellow or caution lamp Y of this signal. On this change in the indication displayed by signal 2S relay 2RMR becomes released to prevent movement 25 of the switch MW, while contacts 36 and 40 of 30 relay 2RMR cut off the supply of energy to the west end of line circuit I and connect the wires of line circuit I directly to the line relays 2P and 2K so that relay 2K will operate at the frequency determined by the rate of operation of 35 coding relay WCR. In addition, on release of relay 2RMR its contact 39 establishes the circuit for supplying energy from the transformer 2DT to relay 2J.

At this time as relay 4H is released its contact 40 50 establishes the circuit controlled by code transmitter 75CT for supplying energy to the coding relay WCR so that this relay supplies energy of 75 code frequency to line circuit I and relay 2K operates at this frequency. As a result 45 too little energy is supplied through the resonant unit RU to pick up the contacts of relay 2J and contact 35 remains released and maintains the circuit of the yellow or caution lamp Y of signal 2S.

50 From the foregoing it will be seen that when an eastbound train passes through the track stretch signal 2S continues to display a stop indication until the train vacates section 3T. When the train advances this far, assuming that the 55 remote control relay 2RHS remains energized, signal 2S is conditioned to display its yellow or caution indication, while relay 2RMR is released to prevent movement of the switch MW, and to 60 cut off the supply of energy to the west end of line circuit I so that signal 3S displays its red or stop indication.

Continuing with consideration of the operation of the equipment in response to passage of the eastbound train, and assuming that a second train has not entered the track stretch and that relay 2RHS remains picked up, when the train advances into section 6T track relay 6TR releases and its contact 105 cuts off the supply of energy to the east end of line circuit II.

70 In addition, when the train enters section 6T signal 6S is conditioned by means, not shown, to display its red or stop indication, while on this change in the aspect of signal 6S relay 6SP releases.

When the train advances far enough to vacate section 5T track relay 5TR picks up, but at this time relay 4SR is maintained picked up by its stick circuit and its contact 107 continues to interrupt the supply of energy to the west end of line circuit II so that on picking up of track relay 5TR energy is not supplied to the line relays 5P and 5K.

When the train advances far enough to vacate section 6T track relay 6TR picks up and its contact 105 establishes the circuit to permit energy to be supplied to line circuit II during the picked-up periods of the contacts of code transmitter 120CT. At this time, as signal 6S displays a stop indication, relay 6SP is released and the energy supplied to line circuit II is of reverse polarity. This energy feeds to line relays 4P and 4K and causes the contacts of relay 4P to occupy their right-hand or reverse position while relay 4K follows code so that energy is supplied through the transformer 4DT to relay 4H so that the contacts of relay 4H pick up. On picking up of its contact 66 the circuit of the red or stop lamp R of signal 4S is interrupted and the circuit including reverse polar contact 67 of relay 4P is established to light the yellow or caution lamp Y of signal 4S.

In addition, on picking up of the contacts of relay 4H its contact 96 interrupts the stick circuit of relay 4SR so that the contacts of relay 4SR release and its contact 107 establishes the circuit to supply energy to the west end of line circuit II. This energy is of normal polarity as relay 3H is picked up and feeds to the line relays 5P and 5K so that the contacts of relay 5P occupy their normal or left-hand positions, while relay 5K responds to coded energy and energy is supplied through the transformer 5DT to the relay 5H. The circuit of relay 5HP continues to be interrupted by contact 78 of relay 5LHS so that contact 79 of relay 5HP remains released and maintains the circuit of the red or stop lamp of signal 5S.

On picking up of the contacts of relay 4H its contacts 55 and 57 establish connections to maintain the supply of energy to the east end of line circuit I after release of the contacts 103 and 104 of relay 4SR.

On picking up of the contacts of relay 4H its contact 50 establishes the circuit controlled by code transmitter 180CT for supplying energy to coding relay WCR so that this relay operates at the 180 rate. Accordingly, relay 2K operates at this higher rate and sufficient energy is supplied through the resonant unit RU to pick up the relay 2J. Contact 85 of relay 2J, therefore, picks up and establishes the circuit of the green or clear lamp G of signal 2S.

As the train proceeds through the track stretch, the signal 6S will again be conditioned to display its green or clear indication, assuming that the remote control apparatus, not shown, continues to cause the signal 6S to be governed by traffic conditions in advance.

When signal 6S again displays its clear indication contacts 87 and 88 of relay 6SP pick up and change the polarity of the energy supplied to the east end of line circuit II from reverse to normal polarity. The contacts of relay 4P, therefore, shift from their reverse to their normal positions and contact 67 establishes the circuit of the green or clear lamp G of signal 4S, while relay 4K continues to follow code and relay 4H is maintained picked up to maintain the supply of energy of normal polarity and 180 code frequency to

line circuit I so that signal 2S continues to display its green or clear indication.

The operation of the equipment on passage of a westbound train through the track stretch is substantially the same as for passage of an eastbound train through the stretch.

When the operator wishes to condition the track stretch for passage of a westbound train he operates the remote control apparatus to energize relay 5LHS, and to cause signal 1S to provide a proceed indication. When relay 5LHS picks up its contact 78 completes the circuit of the relay 5HP which thereupon picks up and its contact establishes the circuit of the yellow or caution lamp of signal 5S. When this signal displays a proceed indication relay 5LMR releases to cut off the supply of energy to the east end of line circuit II and to connect the line circuit directly to the line relays 5P and 5K. In addition, contact 84 of relay 5LMR establishes the circuit to supply energy from transformer 5DT to relay 5J so that relay 5J picks up and its contact 109 establishes the circuit of the green lamp G of signal 5S. At this time relay 3H is picked up and its contact 69 establishes the circuit to supply energy of 180 code frequency to coding relay WCR so that energy of this frequency is supplied to line circuit II. Accordingly, sufficient energy is supplied through the resonant unit RU to pick up relay 5J.

As the supply of energy to the east end of line circuit II is cut off relay 4K ceases to follow code and relay 4H releases and conditions signal 4S to provide its red or stop indication, while release of contacts 55 and 57 of relay 4H changes the energy supplied to the east end of line circuit I from normal to reverse polarity and release of contact 50 of relay 4H changes the energy supplied to relay WCR from 180 to 75 code frequency.

On this change in the polarity of the energy supplied to the east end of line circuit I the polar contacts of line relay 2P shift to their reverse position and its contact 110 interrupts the circuit of relay 2HP to thereby insure that signal 2S will display a stop indication.

When signal 1S is caused to display a proceed indication contacts 30 and 31 of relay 1SP pick up and change the energy supplied to the west end of line circuit I from reverse to normal polarity so that the contacts of relay 3P shift from their reverse to their normal positions and contact 52 establishes the circuit of the green lamp of signal 3S.

When the westbound train enters section 6T track relay 6TR releases and its contact 105 prevents the supply of energy to line circuit II, while its contact 106 interrupts the circuit of relay 5PH so that contact 79 of relay 5HP releases and establishes the circuit of the red or stop lamp R of signal 5S.

In addition, as a result of release of track relay 6TR the detector locking for switch NW becomes effective to prevent picking up of relay 5LMR and thereby prevent movement of switch NW.

For purposes of illustration it will be assumed that the remote control apparatus is arranged so that the relay 5LHS when picked up will not become released when track relay 6TR is released, but will remain picked up until it is released by manipulation of the remote control apparatus by the operator.

When the train advances into section 5T track relay 5TR releases and both shunts and short

circuits line circuit II to insure display of stop indications by signals 4S and 5S.

When the train advances into section 4T track relay 4TR releases and additionally interrupts and short circuits line circuit II, while contacts 43 and 41 of relay 4TR cut off the supply of energy to the east end of line circuit I and connect the relays 3P and 3K directly to the line circuit. As a result of the cutting off of the supply of energy to the east end of line circuit I relay 2H releases and additionally interrupts the circuit of relay 2HP. In addition, release of relay 2H may lock the switch MW, while it may operate indication means to give notice of the approach of the train.

When the train advances into section 3T track relay 3TR releases and interrupts and short circuits line circuit I, while its contact 140 establishes the pick-up circuit of relay 3SR. As a result of interruption of line circuit I relay 3H releases and establishes the holding circuit for relay 3SR, and also establishes the circuit of the red or stop lamp R of signal 3S. In addition, on release of relay 3TR its contacts 90 and 91 prevent the supply of energy to the west end of line circuit II and connect line circuit II directly to the line relays 4P and 4K.

As a result of picking up of the contacts of relay 3SR its contact 54 prevents the supply of energy to the east end of line circuit I, while its contacts 112 and 114 establish circuits to permit the supply of energy to line circuit II on picking up of track relay 3TR.

When the train advances into section 2T track relay 2TR releases and additionally interrupts and short circuits line circuit I.

When the train vacates section 6T contact 106 of track relay 6TR is picked up to permit energy to be supplied to relay 5HP, while contact 105 of track relay 6TR is picked up to permit energy to be supplied to line circuit II. The energy supplied to line circuit II is of reverse polarity as relay 6SP is released since signal 6S is displaying a stop indication.

When track relay 6TR picks up a pick-up circuit is established for relay 5LMR as explained in the patent to McCann mentioned above, and this relay picks up to establish a stick circuit to maintain itself energized as long as signal 5S displays a stop indication, while on picking up of relay 5LMR its contacts 81 and 82 connect the line wires of line circuit II to the contacts of the code transmitter 120CT so that energy may be supplied to the east end of line circuit II.

When the train vacates section 5T track relay 5TR picks up while when the train vacates section 4T track relay 4TR picks up and energy supplied at the east end of line circuit II feeds to line relays 4P and 4K over the circuit which includes back contacts 90 and 91 of relay 3TR. Accordingly, relay 4H picks up and its contact 66 cooperates with reverse polar contact 67 of relay 4P to establish the circuit of the yellow lamp Y of signal 4S.

In addition, on picking up of relay 4H its contacts 55 and 57 establish connections to permit energy to be supplied to the west end of line circuit I. At this time track relay 4TR is picked up, but as track relay 3TR is released, and as contact 54 of relay 3SR is picked up, energy is not supplied to line circuit I.

When the train enters section 1T track relay 1TR releases and its contact 33 interrupts the circuit for supplying energy to the west end of line circuit I, while its contact 34 interrupts the circuit of relay 2HP to insure that this relay will

remain released and maintain the display of a stop indication by signal 2S.

In addition, on release of track relay 1TR signal 1S is conditioned by means not shown to display its red or stop indication, while as a result of this change in the signal 1S relay 1SP releases to cause energy subsequently supplied to line circuit I to be of reverse polarity.

For purposes of illustration it will be assumed 10 that the remote control means, not shown, associated with signal 1S, is unaffected by passage of the train, but is arranged to continue to cause this signal to be governed by traffic conditions in advance until changed by reason of manipulation 15 of the remote control apparatus by the operator.

When the train vacates section 3T track relay 3TR picks up and its contacts 90 and 91 establish the connections over which energy is supplied to the west end of line circuit II. At this time relay 3SR is picked up while relay 3H is released so that energy of normal polarity is supplied to line circuit II. This energy feeds to relays 5P and 5K and relay 5K follows code so 25 that energy is supplied through the transformer 5DT to the relay 5H. The relay 5HP remains released, however, as contact 78 of relay 5LHS is released, and, accordingly, signal 5S continues to display its red or stop indication.

30 When the train advances far enough to vacate section 2T track relay 2TR picks up, but as contact 54 of relay 3SR is picked up energy is not supplied to line circuit I and energy, therefore, is not supplied to relays 2P and 2K. Accordingly, 35 relay 2HP remains released and cannot be picked up and the signal 2S continues to display its stop indication.

When the train advances far enough to vacate section 1T track relay 1TR picks up and its contact 33 establishes the circuit to supply energy to the west end of line circuit I. As pointed out above, at this time relay 1SP is released, while relay 2SL is picked up so that energy of reverse polarity is supplied to line circuit I. This energy feeds to relays 3P and 3K so that energy is supplied through the transformer 3DT to relay 3H. On picking up of relay 3H its contact 51 cooperates with reverse polar contact 52 of relay 3P to establish the circuit of the yellow or caution lamp Y of signal 3S. In addition, on picking up of relay 3H its contact 115 interrupts the stick circuit of relay 3SR, while its contact 69 changes the energy supplied to relay ECR from 75 to 180 50 code frequency.

55 On release of relay 3SR its contact 54 establishes the circuit to supply energy to the east end of line circuit I and this energy feeds to relays 2P and 2K so that relay 2K follows code and energy is supplied through the transformer 2DT to relay 2H. The energy supplied to line circuit I is of normal polarity as contacts 55 and 57 of relay 4H are picked up so that the contacts of relay 2P shift to their normal positions.

60 Although contact 53 of relay 2H, contact 110 of relay 2P, and contact 34 of relay 1TR are closed, relay 2HP remains released as its circuit is interrupted by contact 25 of relay 2RHS so that signal 2S continues to display its red or stop 65 indication.

In addition, on release of relay 3SR its contacts 112 and 114 release, but at this time contacts 60 and 61 of relay 3H are picked up so that energy continues to be supplied to the west end of line circuit II.

Modification shown in Fig. 2

The system shown in Fig. 1 is arranged so that one stop and one caution indication is provided in the rear of a train. However, under some conditions, such as on stretches of downgrade track or where a passing siding is relatively short, one caution indication may not provide adequate warning of the presence of a train. In such situations it is desirable to provide two caution indications in the rear of a train so that a second or following train will have adequate distance in which to stop after receiving a restrictive indication. The system shown in Fig. 2 of the drawings is arranged so that for one direction of traffic two caution indications are provided in the rear of a train in selected stretches.

The system shown in Fig. 2 is similar to that shown in Fig. 1 and identical reference characters are employed in the two figures to identify the elements which are common to both systems.

The system shown in Fig. 1 is arranged so that when an eastbound train is present in section 7T signal 6S will display its red or stop indication, signal 4S will display its yellow or caution indication, while when remote control relay 2RHS is picked up signal 2S will display its green or clear indication.

The system shown in Fig. 2 is arranged so that under the same conditions signal 2S will display its yellow or caution indication.

On passage of a westbound train through the track stretch the system shown in Fig. 2 operates to provide the same signal indications as the system shown in Fig. 1.

In the modification shown in Fig. 2 the portions of the equipment associated with signals 2S and 3S, that is the equipment associated with line circuit I, is substantially the same as that of the corresponding part of Fig. 1. This portion of the equipment differs from that shown in Fig. 1 in that the circuit of the coding relay WCR is controlled by contact 142 of relay HN instead of by contact 50 of relay 4H.

In the modification shown in Fig. 2 the equipment associated with line circuit II differs somewhat from that shown in Fig. 1. In the modification shown in Fig. 2 the coding relay ECR at signal 4S is continuously operated at 75 code frequency, while the line relays 4P and 4K and the associated equipment control the signal 4S and the supply of energy to line circuit I in response to both the frequency and the polarity of the energy supplied over line circuit II instead of in response to coded energy as in the system shown in Fig. 1.

The system shown in Fig. 2 further differs from that shown in Fig. 1 in that the signal 5S is governed only by the polarity of the energy supplied over line circuit II instead of by a combination of polarity and frequency.

The system shown in Fig. 2 also differs from that shown in Fig. 1 in that the frequency of the energy supplied to the east end of line circuit II is controlled by the aspects displayed by signal 6S and the adjacent signal in advance. This control is effected by means of a relay 6SA which is picked up when the signal 6S is displaying either its green or its yellow indication, and by relay 8SA which is picked up when the signal 8S is displaying either its yellow or its green indication.

The equipment is shown in the condition which it assumes when the track stretch is vacant and

the remote control relays are released so that signals 1S, 2S, 5S and 6S display their red or stop indications.

As signal 6S is displaying its stop indication 5 relay 6SA is released and its contact 121 establishes the circuit controlled by code transmitter 120CT for supplying energy to coding relay CR so that the contacts of this relay pick up and release at the 120 code rate.

10 As relay 6SA is released the energy supplied to line circuit II during the picked-up periods of contacts 10 and 11 of coding relay CR is of reverse polarity. This energy feeds to line relays 4P and 4K over the circuit which includes back contacts 123 and 124 of relay HN and back contacts 63 and 64 of relay ECR. As the energy supplied to relay 4P is of reverse polarity contact 67 of relay 4P interrupts the circuit of relay HN and its contacts are released so that energy 15 may be supplied to the west end of line circuit II during the picked-up periods of relay ECR.

In addition, as contact 128 of relay HN is released the circuit for supplying energy from transformer 4DT to relay 4J is interrupted and relay 25 4J is released, and a circuit including front contact 130 of relay 4H and back contact 131 of relay 4J is established to light the yellow or caution lamp Y of signal 4S.

At this time relay 3H is picked up while 4SR is 30 released so that energy of normal polarity is supplied to the line circuit II during the picked-up periods of coding relay ECR. This energy is supplied to relays 5P and 5K during the released periods of coding relay CR so that relay 5K responds to code while contact 125 of relay 5P occupies its left-hand or normal position as shown. At this time remote control relay 5LHS is assumed to be released and its contact 18 interrupts the circuit of relay 5H so that contact 126 of relay 40 5H is released and establishes the circuit of the red or stop lamp R of signal 5S.

As relay HN is released its contact 142 is released and establishes the circuit for supplying energy of 75 code frequency to coding relay WCR.

45 At this time, as explained in detail in connection with the modification shown in Fig. 1, energy of normal polarity is supplied to the east end of line circuit I during the picked-up periods of coding relay WCR, while energy of reverse polarity is supplied to the west end of the line circuit I during the picked-up periods of the contacts of code transmitter 120CT. Accordingly, relay 3K follows code and contact 51 of relay 3H is picked up and cooperates with reverse polar contact 52 of relay 3P to establish the circuit of the yellow lamp Y of signal 3S.

In addition, at this time relay 2K follows code so that relay 2H is picked up while contact 110 60 of relay 2P occupies its normal position as shown. The relay 2RHS is assumed to be released, however, and its contact 25 interrupts the circuit of the relay 2HP so that contact 26 is released and establishes the circuit of the red or stop lamp of signal 2S.

65 As relay 2H is picked up it conditions the locking means, not shown, for switch MW to permit this switch to be moved.

The locking means for switch NW is controlled by relay LR which is energized over a separate line circuit which is governed by track relays 3TR, 4TR and 5TR. As the track stretch is assumed to be vacant relay LR is picked up and permits the switch NW to be moved.

Operation of modification shown in Fig. 2 on passage of an eastbound train

In order to condition the track stretch for movement of an eastbound train the operator manipulates the remote control apparatus to energize relay 2RHS, while he also causes the remote control apparatus to condition signal 6S to be governed by traffic conditions in advance and by the aspect displayed by signal 8S. The means by which this control of signal 6S is effected is not a part of this invention and this signal may be governed by any means well known in the art.

The signal 8S may be an automatic signal governed by traffic conditions in advance or it may be a remotely controlled signal similar to signal 2S which normally displays a stop indication, but which may be governed by remote control apparatus so that it is at times controlled by traffic conditions in advance. In the present case this signal is shown as being at the leaving end of a passing siding and it will be assumed that this signal is controlled in the same manner as signal 2S. It will be assumed also that the operator manipulates the remote control apparatus to cause signal 8S to display an indication determined by traffic conditions in advance and that the track stretch in advance is vacant so that the signal provides its green or clear indication.

As the signal 8S is displaying its green indication signal 6S also displays its green or clear indication so that relays 6SA and 8SA are both picked up and energy of 180 code frequency is supplied to coding relay CR. As contacts 87 and 88 of relay 6SA are picked up energy of normal polarity is supplied to the east end of line circuit II during the picked-up periods of the contacts of relay CR. This energy causes the contacts of relay 4P to shift to their left-hand or normal positions and contact 67 of relay 4P completes the circuit of relay HN so that its contacts 123 and 124 are picked up and cut off the supply of energy to the west end of line circuit II and connect line circuit II directly to the line relays 4P and 4K so that thereafter relay 4K follows the 180 code supplied over the line circuit.

In addition, on picking up of relay HN its contact 128 establishes the circuit to supply energy from the decoding transformer 4DT to relay 4J and as relay 4K is following 180 code sufficient energy is supplied through the resonant rectifier unit RU to pick up the relay 4J. Accordingly, contact 131 of relay 4J interrupts the circuit of the yellow or caution lamp Y and establishes the circuit of the green or clear lamp G of signal 4S.

When the contacts 123 and 124 of relay HN are picked up the supply of energy to the west end of line circuit II during the picked-up periods of the contacts of coding relay ECR is cut off so that relay 5K ceases to follow code and relay 5H will remain released and maintain the display of a red or stop indication by signal 5S even if the remote control apparatus should be manipulated to pick up relay 5LHS.

On picking up of relay HN its contact 142 cuts off the supply of energy of 75 code frequency to coding relay WCR and establishes the circuit to supply energy of 180 code frequency to this relay.

When remote control relay 2RHS is picked up its contact 25 completes the circuit of relay 2HP so that contact 26 of relay 2HP picks up and completes the circuit which includes back contact 85 of relay 2J for lighting the yellow or

caution lamp Y of signal 2S. When signal 2S displays a proceed indication relay 2RMR releases and its contacts 40 and 36 interrupt the supply of energy to the west end of line circuit I and connect the line circuit directly to the line relays 2P and 2K, while contact 39 of relay 2RMR establishes the circuit for supplying energy from the transformer 2DT to relay 2J. As relay 2K is connected directly to the line circuit it operates at 180 code frequency and sufficient energy is supplied through the resonant rectifier unit RU to pick up the relay 2J. Contact 85 of this relay therefore picks up and establishes the circuit of the green or clear lamp G of signal 2S.

15 As a result of releasing of relay 2RMR the locking of switch MW becomes effective to prevent a change in the position of the switch.

As a result of the cutting off of the supply of energy to the west end of line circuit I occasioned by release of the contacts of relay 2RMR relay 3K ceases to follow code and relay 3H releases and its contact 51 establishes the circuit of the red or stop lamp R of signal 3S.

In addition, as a result of the release of relay 25 3H its contacts 60 and 61, which control the polarity of the energy supplied to line circuit II, release, but as relay HN is picked up and interrupts the supply of energy in the line circuit at this time release of relay 3H is without effect.

30 When an eastbound train enters section 1T track relay 1TR releases and its contact 33 interrupts the circuit for supplying energy to the west end of the line circuit I. However, at this time as relay 2RMR is released energy is not supplied to the west end of line circuit I.

35 In addition, on release of track relay 1TR its contact 34 interrupts the circuit of relay 2HP so that its contact 26 releases and establishes the circuit of the red or stop lamp R of signal 2S.

40 When the train advances into section 2T track relay 2TR releases and interrupts and short circuits the line circuit I so that relay 2K ceases to follow code and energy is no longer supplied through the transformer 2DT to relays 2H and 45 2J. Accordingly, relay 2H releases and its contact 58 additionally interrupts the circuit of the relay 2HP so that contact 26 of relay 2HP remains released and maintains the circuit of the red or stop lamp R of signal 2S.

50 On this change in the aspect displayed by signal 2S relay 2RMR may be energized and its contacts 40 and 36 pick up. However, energy cannot be supplied to line circuit I as track relays 1TR and 2TR are released.

55 When the train advances into section 3T track relay 3TR releases and additionally interrupts and short circuits line circuit I. On release of track relay 3TR its contacts 131 and 132 interrupt the circuit of the lock relay LR and this relay releases and locks the switch NW to prevent a change in the position of the switch until after the expiration of a time interval.

60 In addition, on release of track relay 3TR its contacts 90 and 91 interrupt the circuit including the front contacts 123 and 124 of relay HN for connecting the line circuit II to line relays 4P and 4K and connect the line circuit directly to these relays.

When the train enters section 4T track relay 70 4TR releases and its contacts 135 and 136 additionally interrupt the circuit of relay LR, while its contacts 93 and 94 interrupt and short circuit line circuit II, and its contact 95 establishes the pick-up circuit of relay SR.

75 On interruption of the line circuit II relay 4K

ceases to follow code so that energy is no longer supplied to the relays 4H and 4J and these relays release so that contact 139 of relay 4H establishes the circuit of the red or stop lamp R of signal 4S. In addition, on release of relay 4H its contact 96 establishes a stick circuit to maintain relay 4SR picked up, while contact 98 of relay 4H interrupts the circuit of relay HN so that contact 142 of relay HN releases and changes the energy supplied to coding relay WCR from 180 to 75 code frequency. At this time, however, relay 4TR is released and its contacts 43 and 47 connect the wires of line circuit I directly to the line relays 3P and 3K and prevent the supply of energy to the east end of line circuit I.

When the train advances into section 5T track relay 5TR releases and additionally interrupts and short circuits the line circuit II, while contacts 137 and 138 of relay 5TR additionally interrupt the circuit of lock relay LR.

When the train advances into section 6T track relay 6TR releases and causes signal 6S to display its red or stop indication, while release of relay 6TR causes the detector locking for switch NW to be effective. When signal 6S displays its stop indication relay 6SA is released, while when contact 105 of relay 6TR is released it prevents the supply of energy to the east end of line circuit II.

The remote control apparatus for controlling signal 6S may be arranged in the manner well known in the art so that when the apparatus is manipulated to cause this signal to be governed by traffic conditions in advance the signal will continue to be governed in this manner until the remote control apparatus is further manipulated to again cause signal 6S to provide its stop indication regardless of traffic conditions in advance.

When the train advances into section 8T track relay 8TR releases and causes signal 8S to display its red or stop indication so that relay 8SA releases.

When the train vacates section 1T track relay 1TR picks up, and as explained in the above mentioned patent to Ronald A. McCann a pick-up circuit is established for the relay 2RMR and this relay picks up and establishes a stick circuit to maintain itself picked up as long as signal 2S continues to display a stop indication. When the train vacates section 2T track relay 2TR picks up and energy of reverse polarity is supplied to the west end of line circuit I over the back contacts of relay 1SP and the front contacts of relay 2RMR. When the train vacates section 3T track relay 3TR picks up and the energy supplied to line circuit I feeds over the front contacts of track relay 3TR and the back contacts 43 and 47 of relay 4TR to line relays 3P and 3K so that relay 3K follows code and energy is supplied to relay 3H. Accordingly, relay 3H picks up and its contact 51 cooperates with reverse polar contact 52 of relay 3P to establish the circuit of the yellow or caution lamp Y of signal 3S.

When the train vacates section 4T track relay 4TR picks up and its contact 95 interrupts one stick circuit for relay 4SR, but this relay is maintained energized by current supplied over the circuit which includes its own front contact 97 and back contact 96 of relay 4H.

When track relay 4TR picks up its contacts 43 and 47 connect the line wires of line circuit I to the contacts of coding relay WCR so that thereafter the line relays 3P and 3K are energized only during the released periods of the coding relay contacts, while during the picked-up periods of

the coding relay contacts energy of normal polarity is supplied to the line circuit I over back contacts 55 and 57 of relay 4H, and front contacts 103 and 104 of relay 4SR. This energy feeds to line relays 2P and 2K, and relay 2K follows code and energy is supplied through transformer 2DT to relay 2H so that this relay picks up. At this time relay WCR is operating at the 75 code frequency rate as contact 142 of 10 relay HN is released.

It will be assumed that the remote control system is arranged so that the relay 2RHS when picked up remains picked up after passage of a train unless the operator manipulates the remote 15 control apparatus to release this relay. It will be assumed also that the equipment has not been operated to release the relay 2RHS, or if this relay did release that the equipment has been operated to cause it to pick up again.

20 Accordingly, when the train vacates section 4T and energy is supplied to the east end of line circuit I so that relay 2H picks up, the circuit of relay 2HP is complete and the contact 26 of this relay picks up to establish the circuit of the yellow 25 low lamp Y of signal 2S. On this change in the aspect of signal 2S relay 2RMR releases and cuts off the supply of energy to the west end of line circuit I and connects line circuit I directly to line relays 2P and 2K. In addition, contact 39 30 of relay 2RMR establishes the circuit for supplying energy from transformer 2DT to relay 2J. However, at this time relay HN is released and energy of 75 code frequency is supplied to the coding relay WCR so that energy of this frequency 35 is supplied over line circuit I to relay 2K and too little energy is supplied through the resonant rectifier unit RU to pick up relay 2J. Contact 85 of this relay therefore remains released and maintains the circuit of the yellow or caution 40 lamp Y of signal 2S.

On release of relay 2RMR the supply of energy to the west end of line circuit I is cut off and relay 3K therefore ceases to respond to coded 45 energy so that relay 3H releases and its contact 51 establishes the circuit of the red or stop lamp R of signal 3S.

When the train advances far enough to vacate section 5T track relay 5TR picks up. However, at this time relay 4SR is picked up and its contact 59 107 interrupts the supply of energy to the west end of line circuit II so that on picking up of track relay 5TR energy is not supplied to line relays 5P and 5K.

When the train advances far enough to vacate 55 section 6T track relay 6TR picks up and its contact 105 establishes the circuit to supply energy to the east end of line circuit II. Energy may be supplied to the east end of line circuit II at this time as lock relay 5LMR remains picked up since 60 signals 5S and 5SA have continuously displayed stop indications.

When the train vacates section 6T signal 6S continues to display its red or stop indication and relay 6SA remains released so that energy of 65 reverse polarity and 120 code frequency is supplied to the coding relay ECR. This energy feeds to line relays 4P and 4K over the circuit which includes back contacts 123 and 124 of relay HN, and back contacts 63 and 64 of coding relay ECR.

70 As the energy is of reverse polarity the contacts of relay 4P shift to their right-hand or reverse positions and contact 67 interrupts the circuit of relay HN to thereby maintain this relay released so that its contact 128 interrupts the 75 circuit of relay 4J and its contact 142 maintains

the supply of energy of 75 code frequency to coding relay WCR. The energy supplied to relay 4K produces code following operation of this relay so that relay 4H picks up and its contact 130 establishes the circuit of the yellow or caution lamp Y of signal 4S.

When relay 4H picks up its contact 96 interrupts the stick circuit of relay 4SR so that relay 4SR releases and its contact 107 establishes the circuit for supplying energy to the west end of line circuit II. This energy is of reverse polarity as relay 3H is released. This energy feeds to line relays 5P and 5K and produces code following operation of relay 5K, but as relay 5LHS is released energy is not supplied to relay 5H and its contact 126 remains released and maintains the circuit of the red or stop lamp R of signal 5S.

On picking up of the contacts of relay 4H contacts 55 and 57 interrupt one circuit and establish another for supplying energy to the east end of line circuit I so that energy of normal polarity and 75 code frequency continues to be supplied to this circuit and signal 2S continues to display its yellow or caution indication.

It will be seen, therefore, that when an east-bound train advances far enough to vacate section 6T energy of reverse polarity and 120 code frequency is supplied to the right-hand or east end of line circuit II with the result that relay 4H picks up and establishes the circuit of the yellow or caution lamp Y of signal 4S, while contact 67 of relay 4P interrupts the circuit of relay HN. Accordingly, contact 142 of relay HN maintains the supply of energy of 75 code frequency to the east end of line circuit I to maintain the display of the yellow or caution indication by signal 2S. At this time, therefore, the signal 6S displays its red or stop indication, while signals 4S and 2S both display their yellow or caution indications so that there are a red and two yellow signal indications in the rear of the train in section 7T, and a second or following train will have ample warning of the presence of a first train and will have adequate distance in which to stop.

When the train advances far enough to vacate section 7T signal 6S is conditioned by means not shown to display its yellow or caution indication, and on this change in the indication displayed by signal 6S relay 6SA picks up. On picking up of relay 6SA its contacts 87 and 88 change the polarity of the energy supplied to the east end of line circuit II from reverse to normal while contact 121 of relay 6SA interrupts one circuit for supplying energy of 120 code frequency to coding relay CR and establishes the circuit which includes back contact 139 of relay 8SA for supplying energy of 120 code frequency to coding relay CR.

The energy of 120 code frequency and normal polarity supplied over line circuit II causes relay 4H to continue to be energized, while contact 67 of relay 4P is shifted to its left-hand or normal position and completes the circuit of the relay HN. Accordingly, relay HN picks up and its contacts 123 and 124 cut off the supply of energy to the west end of line circuit II and connect the line relays 4P and 4K directly to the line circuit, while contact 142 of relay HN interrupts the circuit for supplying energy of 75 code frequency to relay WCR and establishes the circuit for supplying energy of 180 code frequency to this relay.

On this change in the frequency of the energy supplied to line circuit I relay 2J picks up and

its contact 85 interrupts the circuit of the yellow lamp Y of signal 2S and establishes the circuit of the green or clear lamp G of this signal.

At this time, therefore, signal 8S displays its red indication, while signals 6S and 4S display their yellow indications and signal 2S displays its green or clear indication.

When the train in section 8T advances far enough in the track stretch for signal 8S to display a proceed indication the aspect of signal 6S changes from caution to clear while relay 8SA picks up. Under these conditions the relays 8SA and 6SA are both picked up and energy of 180 code frequency is supplied to coding relay CR over the circuit which includes front contact 139 of relay 8SA and front contact 121 of relay 6SA.

When the relay 4K responds to energy of 180 code frequency, sufficient energy is supplied through the resonant rectifier unit RU to pick up relay 4J. Accordingly, its contact 131 establishes the circuit of the green lamp G of signal 4S.

On this change in the aspect of signal 4S there is no change in the energy supplied to line circuit I and signal 2S continues to display its green or clear indication.

From the foregoing it will be seen that the modification shown in Fig. 2 operates to provide two yellow or caution signals in the rear of a train in a selected portion of the track stretch to thereby provide increased braking distance in these regions.

Operation of the modification shown in Fig. 2 on passage of a westbound train through the track stretch

For purposes of illustration it will be assumed that the track stretch is vacant and that the remote control apparatus is manipulated to condition the track stretch for passage of westbound trains.

In order to condition the stretch for passage of westbound trains the remote control apparatus is manipulated to cause signal 1S to be controlled by traffic conditions in advance, and as the track stretch is assumed to be vacant signal 1S will display its green or clear indication.

The remote control apparatus is also manipulated to pick up relay 5LHS so that signal 5S will provide a proceed indication, while the westbound signals in the rear of signal 5S are also governed so as to provide proceed indications.

When signal 1S displays its green or clear indication contacts 30 and 31 of relay 1SP are picked up so that energy of normal polarity is supplied to the west end of line circuit I. This energy causes the contacts of polar line relay 3P to occupy their left-hand or normal positions and contact 52 establishes the circuit of the green lamp G of signal 3S.

Energy of 75 code frequency and normal polarity continues to be supplied to the west end of line circuit II at this time so that when relay 5LHS is picked up energy is supplied to relay 5H and its contact 126 establishes the circuit which includes normal polar contact 125 of relay 5P to light the green or clear lamp G of signal 5S.

When signal 5S displays a proceed indication relay 5LMR releases to thereby connect the line circuit II directly to line relays 5P and 5K and to cut off the supply of energy to the east end of line circuit II. As a result relay 4K ceases to follow code so that relay 4H releases and its con-

tact 130 establishes the circuit of the red or stop lamp R of signal 4S. When relay 4H releases its contacts 55 and 57 change the energy supplied to the east end of line circuit I from normal to reverse polarity.

On this change in the polarity of the energy supplied to line circuit I contact 110 of relay 2P shifts to its reverse position to interrupt the circuit of relay 2HP and prevent energization of this relay if the remote control apparatus should be manipulated to pick up relay 2RHS.

As relay 2HP is maintained released the signal 2S will display its stop indication, while as relay 2H is picked up the switch MW is not locked but may be moved if desired.

When the train enters section 6T and the track relay 6TR releases the detector locking for switch NW becomes effective. When track relay 6TR releases its contact 105 interrupts the circuit for supplying energy to the east end of line circuit II, while its contact 106 interrupts the circuit of relay 5H so that contact 126 of relay 5H releases and establishes the circuit of the red or stop lamp R of signal 5S.

In addition, as a result of the release of track relay 6TR, the detector locking for switch NW is effective and this switch cannot be moved.

When the train advances into section 5T, track relay 5TR releases and interrupts and short circuits line circuit II so that energy is no longer supplied to the line relays 5P and 5K. Accordingly, energy is no longer supplied through the decoding transformer 5DT and the relay 5H will remain released after contact 106 of track relay 6TR is picked up.

When the train advances into section 4T, track relay 4TR releases and additionally interrupts and short circuits line circuit II, while its contacts 43 and 47 release and cut off the supply of energy to the east end of line circuit I and connect the line wires of line circuit I directly to line relays 3P and 3K so that signal 3S continues to display its green or clear indication.

As a result of interruption of the supply of energy to line circuit I, relay 2K ceases to follow code and energy is no longer supplied to relay 2H and this relay releases to condition the switch locking means, not shown, to lock the switch MW.

When the train advances into section 3T, track relay 3TR releases and interrupts and short circuits line circuit I so that energy is no longer supplied over this circuit to line relays 3P and 3K. Accordingly, relay 3K ceases to follow code and energy is no longer supplied to relay 3H and its contact 51 releases and establishes the circuit of the red or stop lamp R of signal 3S.

In addition, on release of track relay 3TR its contact 140 establishes the pick-up circuit for relay 3ES so that its contact 141 picks up and establishes a stick circuit for the relay. The pick-up circuit for relay 3ES includes front contact 115 of relay 3H, while on release of this contact another stick circuit is established for relay 3ES.

As a result of picking up of relay 3SR, its contact 54 interrupts the circuit for supplying energy to the east end of line circuit I to thereby prevent the supply of energy to this line circuit until the train vacates section 1T.

Furthermore, on release of track relay 3TR its contacts 90 and 91 cut off the supply of energy to the west end of line circuit II and connect the line wires of this line circuit directly to the line relays 4P and 4K.

When the train advances into section 2T, track

relay 2TR releases and additionally interrupts and shunts line circuit I, while when the train enters section 1T, track relay 1TR releases and its contact 33 prevents the supply of energy to the west end of line circuit I, while contact 34 of track relay 1TR releases and interrupts the circuit of relay 2HP so that relay 2HP will remain released and maintain the display of a stop signal by signal 2S.

In addition, on release of track relay 1TR the detector locking for switch MW becomes effective, while signal 1S is conditioned by means not shown to display its red or stop indication.

When the rear of the train vacates section 6T, track relay 6TR picks up and its contact 105 establishes the circuit to permit energy to be supplied to the east end of line circuit II, while contact 106 of track relay 6TR is picked up to permit energy to be supplied to relay 5H.

In addition, on picking up of track relay 6TR a pick-up circuit is established for relay 5LMR, as explained in the patent to McCann, while on picking up of relay 5LMR a stick circuit is established to maintain the relay energized as long as signal 5S displays a stop indication. Also on picking up of relay 5LMR its contacts 81 and 82 establish connection from line wires 22 and 23 to contacts 70 and 71 of coding relay CR so that energy may be supplied to line circuit II.

At this time signal 6S displays its red indication so that relay 6SA is released and the energy supplied to line circuit II is of reverse polarity.

When the train vacates section 5T, track relay 5TR picks up, while when the train vacates section 4T, track relay 4TR picks up and energy supplied to the east end of line circuit II is supplied over back contacts 90 and 91 of track relay 3TR to line relays 4P and 4K. This energy is of reverse polarity so that contact 67 of relay 4P occupies its reverse position and interrupts the circuit of relay 4N and contact 128 of relay 4N is released and interrupts the circuit of relay 4J.

The energy supplied to line relay 4K causes code following operation of this relay and energy is supplied through the transformer 4DT to relay 4H so that contact 130 of relay 4H picks up and establishes the circuit of the yellow or caution lamp Y of signal 4S.

On picking up of track relay 4TR its contacts 43 and 47 connect the line wires of line circuit I to the contacts of coding relay WCR so that energy may be supplied to the west end of line circuit I during the picked-up periods of this relay and may be supplied over the line circuit I to the line relays 3P and 3K during the released periods of the contacts of relay WCR. At this time relay WCR is operated at the 75 code rate as contact 142 of relay 4N is released.

When the train vacates section 3T, track relay 3TR picks up and its contacts 90 and 91 establish the circuit to permit energy to be supplied to the west end of line circuit II and thus to the line relays 5P and 5K. This energy is of reverse polarity as contacts 60 and 61 of relay 3H are released. If the remote control relay 5LHS has remained picked up, or if it became released the remote control apparatus has been manipulated to pick it up again, energy will be supplied through transformer 5DT to relay 5H on code following operation of relay 5K, and contact 126 of relay 5H will pick up and establish the circuit including reverse polar contact 125 of relay 5P to light the yellow or caution lamp Y of signal 5S.

In addition, on picking up of the contacts of

track relay 3TR its contact 40 interrupts one stick circuit for relay 3ES, but this relay is maintained picked up by energy supplied over the stick circuit which includes its own front contact 41 and back contact 45 of relay 3H. As relay 3SR is maintained picked up, its contact 54 continues to prevent the supply of energy to the east end of line circuit I.

When the train advances far enough to vacate section 3T the circuit of the lock relay LR is complete and this relay is picked up to permit the switch NW to be moved.

When the train vacates section 2T, track relay 2TR picks up, but as contact 54 of relay 3SR remains picked up, energy is not supplied to line circuit I and does not feed to line relays 2P and 2K.

When the train advances far enough to vacate section 4T, track relay 4TR picks up and its contact 33 establishes the circuit for supplying energy to the west end of line circuit I. At this time relay 1SP is released so that the energy supplied to line circuit I is of reverse polarity, while relay 2RMR is picked up as signals 2S and 2SA have continued to display stop indications so that energy is supplied to line circuit I. This energy feeds to relays 3P and 3K and relay 3K follows code so that energy is supplied through the transformer 3DT to relay 3H. Accordingly, contact 51 of relay 3H picks up and cooperates with reverse polar contact 52 of relay 3P to establish the circuit of the yellow or caution lamp Y of signal 3S. In addition, contact 45 of relay 3H interrupts the stick circuit of relay 3ES so that contact 54 of relay 3ES releases and establishes the circuit to supply energy to the east end of line circuit I. At this time relay 4H is picked up so that the energy supplied to line circuit I is of normal polarity.

The energy supplied to the east end of line circuit I feeds to line relays 2P and 2K and relay 2K follows code so that energy is supplied through transformer 2DT to relay 2H, while contact 40 of relay 2P occupies its normal position as shown. However, until the remote control relay 2RHS is energized, relay 2HP remains released and maintains the circuit of the red or stop lamp R of signal 2S. As relay 2RMR is picked up, its contact 39 interrupts the circuit of the relay 2J and this relay remains released.

When the train advances far enough in the track stretch for the signal 1S to again display its green or clear indication, relay 1SP picks up and changes the energy supplied to the west end of line circuit I from reverse to normal polarity. As a result, the contacts of relay 4P shift from their reverse to their normal positions and contact 52 establishes the circuit of the green or clear lamp of signal 3S.

From the foregoing it will be seen that when a westbound train passes through the track stretch, signal 5S will display its red or stop indication until the train vacates section 3T, and that signal 3S will display its red or stop indication until the train vacates section 4T. When the train vacates section 4T, signal 1S displays its stop indication, while signal 3S displays its caution indication, and signal 5S displays its green or clear indication. Accordingly, a second or following westbound train will receive only one caution indication before reaching a signal displaying a stop indication.

Although the modification shown in Fig. 2 of the drawings has been illustrated and described as providing two caution indications in the rear

of an eastbound train and one caution indication in the rear of a westbound train, it is obvious that the equipment may be arranged to provide two caution indications in the rear of a westbound train and one caution indication in the rear of an eastbound train.

Similarly the equipment shown in Fig. 2 may be arranged to provide two caution indications in the rear of trains traveling in each direction. 10 This method of operation may be secured by substituting for the equipment associated with line circuit I equipment arranged in the same manner as that associated with line circuit II.

In such a modification energy of 75 code frequency would be supplied to the east end of line circuit I, while this energy would be of normal or reverse polarity according to whether relay 4H is picked up or released.

The frequency and polarity of the energy supplied to the west end of line circuit I would be governed in the same manner as the energy supplied to the east end of line circuit II is controlled, while the supply of energy to the east end of line circuit I and to the west end of line circuit II will be controlled by the directional stick relays as at present. In addition, in such a modification the approach locking of the switch MW will be controlled over a separate line circuit similar to that for controlling switch NW.

30 From the foregoing it will be seen that this invention provides an improved signaling system adapted for use in track stretches in which the signals are governed by remote control apparatus. The system is arranged so that when the remote control apparatus has been manipulated to clear the signals for one direction of traffic, the energy supplied to the line circuits for controlling the signals for the other direction of traffic is either cut off or its polarity is changed so that the signals for such other direction of traffic cannot be conditioned to provide proceed indications.

It will be seen also that some modifications of this invention provide means not only for controlling the signals for both directions of traffic 45 over one line circuit but also provide means operative over the same line circuit for controlling locking of the switches at the passing sidings.

In addition, it will be seen that the system provided by this invention enables more than one caution indication to be provided in the rear of a train in selected locations if desired.

The system provided by this invention at times makes use of mutilated code generated by operation of coding devices at opposite ends of a line circuit at different rates, and at such times the frequency responsive portions of the equipment 55 is rendered inoperative so that it is unaffected by the irregular code. When the frequency responsive apparatus is intended to function, the coding device at that end of the line circuit is cut out and the line relays are connected directly to the line circuit so that accurate unmutilated code is supplied to the line relays at such times.

Although I have herein shown and described 60 only two forms of railway signaling system embodying my invention, it is understood that various changes and modifications may be made therein within the scope of the appended claims without departing from the spirit and scope of my invention.

Having thus described my invention, what I claim is:

1. In combination, a stretch of railroad track having a pair of track rails over which traffic moves in both directions, the rails of the track

stretch being divided by insulated joints into a plurality of track sections including an intermediate section having at one side a first section and at the other side a second section, a first signal governing movement of traffic from the first section into the intermediate section, a second signal governing movement of traffic from the second section into the intermediate section, a pair of control conductors substantially coextensive with and controlled by traffic conditions in said intermediate section, a first coding device and a first electroresponsive device at the end of the control conductors adjacent said first signal, a second coding device and a second electroresponsive device at the end of the control conductors adjacent said second signal, each of said coding devices having contacts continuously actuated between a position in which they establish connection from the control conductors to the associated electroresponsive device and a position in which they permit connection to be established between said control conductors and a source of current, each of said electroresponsive devices controlling the associated signal, and means effective on the display of a proceed indication by the first signal to connect the first electroresponsive device directly to the control conductors and to interrupt the supply of energy to the control conductors over the connections controlled by said first coding device.

2. In combination, a stretch of railroad track having a pair of track rails over which traffic moves in both directions, the rails of the track stretch being divided by insulated joints into a plurality of track sections including an intermediate section having at one side a first section and at the other side a second section, a first signal governing movement of traffic from the first section into the intermediate section, a second signal governing movement of traffic from the second section into the intermediate section, a pair of control conductors substantially coextensive with and controlled by traffic conditions in said intermediate section, a first coding device and a first electroresponsive device at the end of the control conductors adjacent said first signal, a second coding device and a second electroresponsive device at the end of the control conductors adjacent said second signal, each of said coding devices having contacts continuously actuated between a position in which they establish connection from the control conductors to the associated electroresponsive device and a position in which they permit connection to be established between said control conductors and a source of current, each of said electroresponsive devices controlling the associated signal, and means effective on the display of a proceed indication by the first signal to interrupt the supply of energy to the control conductors over the connections controlled by said first coding device.

3. In combination, a stretch of railroad track having a pair of track rails over which traffic moves in both directions, the rails of the track stretch being divided by insulated joints into a plurality of track sections including an intermediate section having at one side a first section and at the other side a second section, a first signal governing movement of traffic from the first section into the intermediate section, a second signal governing movement of traffic from the second section into the intermediate section, a pair of control conductors substantially coextensive with and controlled by traffic conditions

in said intermediate section, a first coding device and a first electroresponsive device at the end of the control conductors adjacent said first signal, a second coding device and a second electroresponsive device at the end of the control conductors adjacent said second signal, each of said coding devices having contacts continuously actuated between a position in which they establish connection from the control conductors to the associated electroresponsive device and a position in which they permit connection to be established between said control conductors and a source of current, the second electroresponsive device controlling the second signal, means governed by said first electroresponsive device and by manually controlled means for controlling said first signal, and means effective on the display of a proceed indication by said first signal to interrupt the supply of energy to the control conductors over the connections controlled by said first coding device.

4. In combination, a stretch of railroad track having a pair of track rails over which traffic moves in both directions, the rails of the track stretch being divided by insulated joints into a plurality of track sections including an intermediate section having at one side a first section and at the other side a second section, a first signal governing movement of traffic from the first section into the intermediate section, a second signal governing movement of traffic from the second section into the intermediate section, a pair of control conductors substantially coextensive with and controlled by traffic conditions in said intermediate section, a first coding device and a first electroresponsive device at the end of the control conductors adjacent said first signal, a second coding device and a second electroresponsive device at the end of the control conductors adjacent said second signal, each of said coding devices having contacts continuously actuated between a position in which they establish connection from the control conductors to the associated electroresponsive device and a position in which they permit connection to be established between said control conductors and a source of current, the contacts of the first coding device being operated at a first rate and the contacts of the second coding device being operated at times at a second rate and at other times at a third rate, the second electroresponsive device controlling the second signal, means governed by the first electroresponsive device for controlling said first signal, said first electroresponsive device selectively controlling said first signal in accordance with the rate of supply of impulses of energy thereto and thereby in accordance with the rate of operation of the second coding device, and means effective on the display of a proceed indication by the first signal to interrupt the supply of energy to the control conductors over the connections controlled by said first coding device and to connect said first electroresponsive means directly to said control conductors.

5. In combination, a stretch of railroad track having a pair of track rails over which traffic moves in both directions, the rails of the track stretch being divided by insulated joints into a plurality of track sections including an intermediate section having at one side a first section and at the other side a second section, a first signal governing movement of traffic from the first section into the intermediate section, a second signal governing movement of traffic from the second section into the intermediate section, a pair of control conductors substantially coextensive with and controlled by traffic conditions

second section into the intermediate section, a pair of control conductors substantially coextensive with and controlled by traffic conditions in said intermediate section, a first coding device and a first electroresponsive device at the end of the control conductors adjacent said first signal, a second coding device and a second electroresponsive device at the end of the control conductors adjacent said second signal, each of said coding devices having contacts continuously actuated between a position in which they establish connection from the control conductors to the associated electroresponsive device and a position in which they permit connection to be established between said control conductors and a source of current, the contacts of the first coding device being operated at a first rate and the contacts of the second coding device being operated at times at a second rate and at other times at a third rate, the second electroresponsive device controlling said second signal, a first and a second auxiliary relay associated with said first electroresponsive device, the first auxiliary relay being picked up whenever said electroresponsive device is responding to coded energy, the second auxiliary relay being picked up only when said electroresponsive device is responding to coded energy of the frequency supplied when the contacts of said second coding device are operated at said second rate, means governed by said first auxiliary relay for conditioning said first signal to display one proceed indication, means effective on the display of a proceed indication by said first signal to interrupt the supply of energy to the control conductors over the connections controlled by said first coding device to connect said first electroresponsive device directly to said control conductors and to establish the circuit of said second auxiliary relay, and means governed by said second auxiliary relay for conditioning said first signal to display another proceed indication.

6. In combination, a stretch of railroad track having a pair of track rails over which traffic moves in both directions, the rails of the track stretch being divided by insulated joints into a plurality of track sections including an intermediate section having at one side a first section and at the other side a second section, a first signal governing movement of traffic from the first section into the intermediate section, a second signal governing movement of traffic from the second section into the intermediate section, a pair of control conductors substantially coextensive with and controlled by traffic conditions in said intermediate section, a first coding device and a first electroresponsive device at the end of the control conductors adjacent said first signal, a second coding device and a second electroresponsive device at the end of the control conductors adjacent said second signal, each of said coding devices having contacts continuously actuated between a position in which they establish connection from the control conductors to the associated electroresponsive device and a position in which they permit connection to be established between said control conductors and a source of current, means for causing the energy supplied to the control conductors over the connections controlled by the contacts of the second coding device to be of normal polarity at times and of reverse polarity at other times, the second electroresponsive device controlling said second signal, means governed by the first electroresponsive device for controlling said first signal, said

means being effective to cause said signal to display a proceed indication only when energy of normal polarity is supplied to said first electroresponsive device, and means effective on the display of a proceed indication by said first signal to interrupt the supply of energy to the control conductors over the connections controlled by said first coding device.

7. In combination, a stretch of railroad track having a pair of track rails over which traffic moves in both directions, the rails of the track stretch being divided by insulated joints into a plurality of track sections including an intermediate section having at one side a first section and at the other side a second section, a first signal governing movement of traffic from the first section into the intermediate section, a second signal governing movement of traffic from the second section into the intermediate section, a pair of control conductors substantially coextensive with and controlled by traffic conditions in said intermediate section, a first coding device and a first electroresponsive device at the end of the control conductors adjacent said first signal, a second coding device and a second electroresponsive device at the end of the control conductors adjacent said second signal, each of said coding devices having contacts continuously actuated between a position in which they establish connection from the control conductors to the associated electroresponsive device and a position in which they permit connection to be established between said control conductors and a source of current, means for causing the energy supplied to the control conductors over the connections controlled by the contacts of the second coding device to be of normal polarity at times and of reverse polarity at other times, the second electroresponsive device controlling the second signal, a first and a second auxiliary relay associated with the first electroresponsive device, means effective when said first electroresponsive device is supplied with coded energy of either polarity for energizing said first auxiliary relay, and means effective when said first section is unoccupied, the first auxiliary relay is energized, and the first electroresponsive device is supplied with energy of normal polarity to energize the second auxiliary relay, said second auxiliary relay being effective when energized to cause said first signal to display a proceed indication.

8. In combination, a single track railroad having a stretch of single track between two passing sidings, said single track stretch being divided by insulated joints into a first and a second section, a first headblock signal governing entrance of trains moving in one direction into the first track section and a second headblock signal governing entrance of trains moving in the other direction into the second track section, a first intermediate signal governing movement of trains from the second section into the first section, a second intermediate signal governing movement of trains from the first section into the second section, a first pair of control conductors substantially coextensive with said first track section, a second pair of control conductors substantially coextensive with said second track section, each pair of control conductors having at each end thereof a coding device and an electro-responsive device, each of said coding devices having contacts continuously actuated between a position in which they establish connection from the control conductors to the associated electroresponsive device and a position in

which they permit connection to be established between a source of current and the control conductors, the electroresponsive device at the intermediate location which is energized over the first pair of control conductors controlling the first intermediate signal and also controlling the polarity of the energy supplied to the adjacent end of the second pair of control conductors, the electroresponsive device at the intermediate location which is energized over the second pair of control conductors controlling the second intermediate signal and also controlling the polarity of the energy supplied to the adjacent end of the first pair of control conductors, the electroresponsive devices at the headblock ends of the control conductors being selectively responsive to the polarity of the energy supplied thereto and controlling the associated signal, and means at each headblock location operative on the display of a proceed indication by such signal to cut off the supply of energy to the adjacent end of the associated control conductors.

9. In combination, a single track railroad having a stretch of single track between two passing sidings, said single track stretch being divided by insulated joints into a first and a second section, a first headblock signal governing entrance of trains moving in one direction into the first track section and a second headblock signal governing entrance of trains moving in the other direction into the second track section, a first intermediate signal governing movement of trains from the second section into the first section, a second intermediate signal governing movement of trains from the first section into the second section, a first pair of control conductors substantially coextensive with said first track section, a second pair of control conductors substantially coextensive with said second track section, each pair of control conductors having at each end thereof a coding device and an electroresponsive device, each of said coding devices having contacts continuously actuated between a position in which they establish connection from the control conductors to the associated electroresponsive device and a position in which they permit connection to be established between a source of current and the control conductors, the contacts of the coding devices at the headblock ends of the control conductors being operated at a first rate, the contacts of the coding devices at the intermediate signal ends of the control conductors being operated at a second or a third rate to thereby supply energy of a second or third code frequency to said control conductors, the electroresponsive device at the intermediate location which is energized over the first pair of control conductors controlling the first intermediate signal and also determining whether the contacts of the coding device at the adjacent end of the second pair of control conductors operate at said second or third rate, the electroresponsive device at the intermediate location which is energized over the second pair of control conductors controlling the second intermediate signal and also determining whether the contacts of the coding device at the adjacent end of the first pair of control conductors operate at said second or third rate, the electroresponsive devices at the headblock ends of the control conductors each controlling the associated headblock signal according as energy of the second or third frequency is supplied thereto, and means associated with each headblock signal and operative on the display of a proceed indication by such signal to

cut off the supply of energy to the adjacent end of the associated control conductors and to connect the associated electroresponsive device directly to the control conductors.

- 5 10. In combination, a single track railroad having a stretch of single track between two passing sidings, said single track stretch being divided by insulated joints into a first and a second section, a first headblock signal governing entrance
10 of trains moving in one direction into the first track section and a second headblock signal governing entrance of trains moving in the other direction into the second track section, a first intermediate signal governing movement of trains
15 from the second section into the first section, a second intermediate signal governing movement of trains from the first section into the second section, a first pair of control conductors substantially coextensive with said first track section, a second pair of control conductors substantially coextensive with said second track section, each pair of control conductors having at each end thereof a coding device and an electroresponsive device, each of said coding devices having contacts
20 continuously actuated between a position in which they establish connection from the control conductors to the associated electroresponsive device and a position in which they permit connection to be established between a source of current and the control conductors, the contacts of the coding devices at the headblock ends of the control conductors being operated at a first rate, the contacts of the coding devices at the intermediate signal ends of the control conductors being operated at a second or a third rate to thereby supply energy of a second or third code frequency to said control conductors, the electroresponsive device at the intermediate location which is energized over the first control conductors controlling the first intermediate signal and also determining the polarity of the energy supplied to the adjacent end of the second control conductors and whether the contacts of the coding device at said adjacent end of the second control
45 conductors are operated at the second or the third rate, the electroresponsive device at the intermediate location which is energized over the second control conductors controlling the second intermediate signal and also determining the polarity of the energy supplied to the adjacent end of the first control conductors and whether the contacts of the coding device at said adjacent end of the first control conductors are operated at the second or the third rate, the electroresponsive devices at the headblock ends of the control conductors each controlling the associated headblock signal according as energy of one or the other polarity and of the second or the third frequency is supplied thereto, and means associated with each headblock signal and operative on the display of a proceed indication by such signal to cut off the supply of energy to the adjacent end of the associated control conductors and to connect the associated electroresponsive device directly to the control conductors.
11. In combination, a single track railroad having a stretch of single track between two passing sidings, said single track stretch being divided by insulated joints into a first and a second section, a first overlap section at the end of the first section remote from the second section, a second overlap section at the end of the second section remote from the first section, a first headblock signal governing entrance of trains from the first
75 overlap section into the first section, a second

headblock signal governing entrance of trains from the second overlap section into the second track section, a first intermediate signal governing movement of trains from the second section into the first section, a second intermediate signal governing movement of trains from the first section into the second section, a first pair of control conductors substantially coextensive with and controlled by traffic conditions in the first track section, a second pair of control conductors substantially coextensive with and controlled by traffic conditions in the second track section, each pair of control conductors having at each end thereof a coding device and an electroresponsive device, each of said coding devices having contacts continuously actuated between a position in which they establish connection from the control conductors to the associated electroresponsive device and a position in which they permit connection to be established between a source of current to the control conductors, the electroresponsive device at the intermediate signal location which is energized over the first control conductors controlling the first intermediate signal, the electroresponsive device at the intermediate signal location which is energized over the second control conductors controlling the second intermediate signal, the electroresponsive devices at the headblock ends of the control conductors controlling the associated headblock signals, a first directional stick relay effective when energized to prevent the supply of energy to the first control conductors at the intermediate signal end thereof, a second directional stick relay effective when energized to prevent the supply of energy to the second control conductors at the intermediate signal end thereof, means effective to energize the first directional stick relay when the electroresponsive device at the intermediate end of the first track section is deenergized as a result of occupation of the first track section by a train entering the section from the second section, means effective to energize the second directional stick relay when the electroresponsive device at the intermediate end of the second track section is deenergized as a result of occupation of the second track section by a train entering the section from the first section, means effective when the first overlap section is occupied to prevent the supply of energy to the adjacent end of the first control conductors, and means effective when the second overlap section is occupied to prevent the supply of energy to the adjacent end of the second control conductors.

12. In combination, a stretch of railroad track having a pair of track rails over which traffic moves in both directions, the rails of the track stretch being divided by insulated joints into a plurality of track sections including an intermediate section having at one side a first section and at the other side a second section, a first signal governing movement of traffic from the first section into the intermediate section, a second signal governing movement of traffic from the second section into the intermediate section, a pair of control conductors substantially coextensive with and controlled by traffic conditions in said intermediate section, a first coding device and a first electroresponsive device at the end of the control conductors adjacent said first signal, a second coding device and a second electroresponsive device at the end of the control conductors adjacent said second signal, each of said coding devices having contacts continuously actuated between a position in which they establish

- connection from the control conductors to the associated electroresponsive device and a position in which they permit connection to be established between said control conductors and a source of current, the contacts of the first coding device being operated at a first rate and the contacts of the second coding device being operated at times at a second rate and at other times at a third rate, means for causing the energy supplied to the control conductors over the connections controlled by the contacts of the second coding device to be of normal polarity at times and of reverse polarity at other times, said second electroresponsive device controlling the second signal, a first and a second auxiliary relay associated with the first electroresponsive device, means effective when said first electroresponsive device is supplied with coded energy of either polarity for energizing said first auxiliary relay and means effective only when said first electroresponsive device is supplied with coded energy of normal polarity and of said third rate to energize said second auxiliary relay, said first and second auxiliary relays controlling said first signal.
13. In combination, a stretch of railroad track having a pair of track rails over which traffic moves in both directions, the rails of the track stretch being divided by insulated joints into a plurality of track sections including an intermediate section having at one side a first section and at the other side a second section, a first signal governing movement of traffic from the first section into the intermediate section, a second signal governing movement of traffic from the second section into the intermediate section, a pair of control conductors substantially coextensive with and controlled by traffic conditions in said intermediate section, a first coding device and a first electroresponsive device at the end of the control conductors adjacent said first signal, a second coding device and a second electroresponsive device at the end of the control conductors adjacent said second signal, each of said coding devices having contacts continuously actuated between a position in which they establish connection from the control conductors to the associated electroresponsive device and a position in which they permit connection to be established between said control conductors and a source of current, the contacts of the first coding device being operated at a first rate and the contacts of the second coding device being operated at times at a second rate and at other times at a third rate, means for causing the energy supplied to the control conductors over the connections controlled by the contacts of the second coding device to be of normal polarity at times and of reverse polarity at other times, said second electroresponsive device controlling the second signal, a first and a second auxiliary relay associated with the first electroresponsive device, means effective when said first electroresponsive device is supplied with coded energy of either polarity and of either said second or third rate to energize said first auxiliary relay, and means effective only when said first electroresponsive device is supplied with coded energy of normal polarity and of said third rate to energize said second auxiliary relay, said first and second auxiliary relays controlling said first signal.
14. In a signaling system for a stretch of railway track having a track section through which traffic may move in either direction, in combination, a pair of conductors substantially coexten-

sive with and governed by traffic conditions in said track section, a first signal governing entrance of traffic in one direction into said track section, a second signal governing entrance of traffic in the other direction into said track section, a first coding device and a first electroresponsive device at the end of said conductors adjacent the first signal, a second coding device and a second electroresponsive device at the end of the conductors adjacent the second signal, each of said coding devices having contacts continuously actuated between a position in which they establish connection from said conductors to the associated electroresponsive device and a position in which they permit connection to be established between said conductors and a source of current, the contacts of said first and second coding devices being operated at substantially different speeds so that there are frequently recurring periods during which energy may be supplied to each of said electroresponsive devices, means for each signal effective to cause the display of a proceed indication by said signal only when the electroresponsive device associated with said signal is supplied with coded energy, means for at times maintaining the display of the stop indication by said first signal, and means effective on the display of a proceed indication by said first signal to prevent the supply of energy to said conductors over the contacts of said first coding device.

15. In a signaling system for a stretch of railway track having a track section through which traffic may move in either direction, in combination, a pair of conductors substantially coextensive with and governed by traffic conditions in said track section, a first signal governing entrance of traffic in one direction into said track section, a second signal governing entrance of traffic in the other direction into said track section, a first coding device and a first electroresponsive device at the end of said conductors adjacent the first signal, a second coding device and a second electroresponsive device at the end of the conductors adjacent the second signal, each of said coding devices having contacts continuously actuated between a position in which they establish connection from said conductors to the associated electroresponsive device and a position in which they permit connection to be established between said conductors and a source of current, the contacts of said first and second coding devices being operated at substantially different speeds so that there are frequently recurring periods during which energy may be supplied to each of said electroresponsive devices,

means for each signal effective to cause the display of a proceed indication by said signal only when the electroresponsive device associated with said signal is supplied with coded energy, means for at times maintaining the display of the stop indication by said first signal, and means effective on the display of a proceed indication by said first signal to prevent the supply of energy to said conductors over the contacts of said first coding device and to connect said first electroresponsive device to said conductors independently of the contacts of said first coding device.

16. In a signaling system for a stretch of railway track having a track section through which traffic may move in either direction, in combination, a pair of conductors substantially coextensive with and governed by traffic conditions in said track section, a first signal governing entrance of traffic in one direction into said track section, a second signal governing entrance of traffic in the other direction into said track section, a first coding device and a first electroresponsive device at the end of said conductors adjacent the first signal, a second coding device and a second electroresponsive device at the end of the conductors adjacent the second signal, each of said coding devices having contacts continuously actuated between a position in which they establish connection from said conductors to the associated electroresponsive device and a position in which they permit connection to be established between said conductors and a source of current, the contacts of the first coding device being operated at a first rate and the contacts of the second coding device being operated at times at a second rate and at other times at a third rate, said second electroresponsive device controlling said second signal, said first electroresponsive device selectively controlling said first signal in accordance with the rate of supply of impulses of energy thereto and thereby in accordance with the rate of operation of the second coding device, means for each signal effective to cause the display of a proceed indication by said signal only when the electroresponsive device associated with said signal is supplied with coded energy, means for at times maintaining the display of the stop indication by said first signal, and means effective on the display of a proceed indication by said first signal to prevent the supply of energy to said conductors over the contacts of said first coding device and to connect said first electroresponsive device to said conductors independently of the contacts of said first coding device.

THOMAS W. TIZZARD, JR.
